UNITED STATES PATENT OFFICE.

JOHN E. BELL, OF BROOKLYN, NEW YORK, ASSIGNOR TO COMBUSTION ENGINEERING CORPORATION, A CORPORATION OF NEW YORK.

FURNACE APPARATUS.

Application filed September 16, 1922. Serial No. 583,565.

This invention relates to furnace apparatus and it is especially useful in connection with stationary boilers burning pulverized fuel.

5 One of the primary objects of my invention is to provide an improved arrangement of cooling screen for preventing the formation of slag, which is simple and effective in construction, the parts of which are easily 10 installed and readily accessible, and in which provision is made for contraction and expansion.

The foregoing, together with such other objects as may hereinafter appear or are incident to my invention, I obtain by means 15 of a construction which I have illustrated in preferred form in the accompanying drawing, wherein:

20 Fig. 1 is a section through a boiler and furnace embodying my improvements; and Fig. 2 is a section taken on the line 2—2 of Fig. 1.

25 In the drawing I have shown my improvements in connection with a boiler of substantially the horizontal type, as the invention is particularly useful in combination therewith. This boiler comprises one or more drums 7; the downcomer header or headers 8; the upcomer header or headers 9; and the 30 connecting bank of tubes 10, such tubes being suitably baffled, one baffle, however, 10^a rising from the bridge wall 20.

The tubes 10 extend over the outlet 11 of the combustion chamber A, such outlet being 35 located in the upper part thereof and the combustion chamber being of such size that combustion is completed therein.

40 The pulverized fuel is admitted by one or more burners B which may be of any preferred construction and are located in the top wall 12 of the combustion chamber in a position to discharge the coal vertically downward, adjacent the front wall 13. The fuel and flame stream takes a U-shaped course 45 through the combustion chamber under the influence of the draft creating means, the bend in the stream being substantially above the bottom 14 of the combustion chamber.

50 About ten per cent of the air needed for combustion is supplied through the burner mechanism and the additional air needed to complete combustion is provided through a battery of inlet openings 15 formed in the front wall 13.

55 In the bottom of the combustion chamber I

provide a water screen C composed of oppositely inclined sets of tubes 16 and 17 which are connected into the header 18 at their forward ends, such header being preferably suitably anchored. The tubes 17 are connected into the header 19 at the rear of the bridge wall 20, and the tubes 16 are similarly connected to the header 21. A plurality of pipes 22 connect the header 21 with the downcomer header 8. These pipes 22 are 60 preferably arranged in two groups of three each at the ends of the header 21, although the number thereof may be varied as the demands of the particular installation require. The pipes 22 are anchored in the floor 65 23 and the portions thereabove are bent so as to take care of expansion and contraction. The pipes 16 and 17 expand from the front to the rear.

In operation the screen C absorbs radiant 70 heat from the deposit collecting on the floor 14 so as to maintain the temperature of such deposit below the fusion or slagging point, the deposit remaining in the form of a fine ash which is readily removable.

In order to protect the bridge wall 20 from erosion, I provide a screen D composed of a plurality of pipes 24, such pipes having their lower ends connected into the header 19, the main portion of the tubes lying within the combustion chamber and extending substantially vertically upward along the bridge wall 20. The upper ends of the tubes 24 extend rearwardly through the bridge wall and are connected into a header 25, which in 90 turn is connected with one or more of the lowermost tubes 10^a of the boiler, the rear of such tubes being downwardly bent, as indicated, for this purpose. The header 25 is anchored, as indicated at 26. Expansion and 95 contraction of the tubes 24 between the headers 19 and 25 is taken care of by virtue of the bends in such pipes.

The screen D operates to cool the deposit collecting on the bridge wall 20 below the 100 slag forming temperature. This deposit builds out in the form of "whiskers" or hair-like horns, formed by particles building out in a direction against the flow of the fuel and flame stream, the deposit breaking off 105 of its own weight.

The space between the tubes 24 is such as to permit this deposit to fall to the bottom of the combustion chamber. If the deposit on the rear wall were permitted to slag 110

it would, in running down, wash away the bridge wall.

The arrangement and connection for the screens is simple and effective, the various parts are easy to install and are readily accessible from the exterior of the combustion chamber.

Other advantages will occur to those skilled in the art.

10. What I claim is:

1. In a pulverized fuel burning furnace, the combination of a boiler having tubes; a combustion chamber; a cooling screen in the bottom of the chamber marginally of the zone of combustion including two sets of tubes, a header with which both sets are connected at one end, and header for each set at the other end; pipes connected to one of said last mentioned headers at one end and anchored at the other end; means connecting said pipes with the downcomer header of the boiler; a second cooling screen marginally of the combustion zone composed of tubes connected with the other of said headers at one end; and a header with which the tubes of the second cooling screen are connected at the other end; said last header being connected with a tube of the boiler.
2. In a pulverized fuel burning furnace, the combination of a boiler having tubes; a combustion chamber; a cooling screen in the bottom of the chamber marginally of the zone of combustion including two sets of tubes, a header with which both sets are connected at one end, and header for each set at the other end; pipes connected to one of said last mentioned headers at one end and anchored at the other end; means connecting said pipes with the downcomer header of the boiler; a second cooling screen marginally of the combustion zone composed of tubes connected with the other of said headers at one end; and a header with which the tubes of the second cooling screen are connected at the other end; said last header being connected with a tube of the boiler and being anchored; and the header common to both of said sets of tubes of the first screen being anchored.
3. In combination, a combustion chamber for burning fuel in suspension having an outlet in its upper part for the products of combustion, a boiler over said outlet, a cooling stream above the floor of the chamber and marginal of the zone of combustion and composed of tubes spaced apart to permit refuse particles to pass freely therebetween to the said floor, said screen tubes being arranged in two rows in substantially V-form, a header at the apex of the V common to both rows, a header for each row into which the opposite ends of the respective row are connected, said headers being exterior of the chamber, a downcomer leading from the boiler to the lower of said last two headers, a second substantially upright screen within the chamber marginal of the zone of combustion and composed of a row of tubes, the lower ends of which are connected with the upper of said last two headers, an anchored header exterior of the chamber with which the upper ends of said tubes of the upright screen are connected, means connecting said last header into the circulation of the boiler, and means for introducing the fuel to be burned in suspension.
4. In combination, a combustion chamber for burning fuel in suspension having an outlet in its upper part for the products of combustion, a boiler over said outlet, a cooling screen above the floor of the chamber and marginal of the zone of combustion and composed of tubes spaced apart to permit refuse particles to pass freely therebetween to the said floor, said screen tubes being arranged in two rows in substantially V form, an anchored header at the apex of the V common to both rows, a header for each row into which the opposite ends of the respective row are connected, said headers being exterior of the chamber, a downcomer leading from the boiler to the lower of said last two headers, means for anchoring said downcomer, a second substantially upright screen within the chamber marginal of the zone of combustion and composed of a row of tubes, the lower ends of which are connected with the upper of said last two headers, an anchored header exterior of the chamber with which the upper ends of said tubes of the upright screen are connected, means connecting said last header into the circulation of the boiler and means for introducing the fuel to be burned in suspension.
5. In combination, a combustion chamber for burning fuel in suspension having an outlet in its upper part for the products of combustion, a boiler over said outlet, a cooling screen above the floor of the chamber and marginal of the zone of combustion and composed of tubes spaced apart to permit refuse particles to pass freely therebetween to the said floor, said screen tubes being arranged in two rows in substantially V form, an anchored header at the apex of the V common to both rows, a header for each row into which the opposite ends of the respective row are connected, said headers being exterior of the chamber, a downcomer leading from the boiler to the lower of said last two headers, a second substantially upright screen within the chamber marginal of the zone of combustion and composed of a row of tubes, the lower ends of which are connected with the upper of said last two headers, an anchored header exterior of the chamber with which the upper ends of said tubes of the upright screen are connected, means connecting said last header into the circulation of the boiler, and means for introducing the fuel to be burned in suspension.

troducing the fuel to be burned in suspen-
sion.

6. In a pulverized fuel burning furnace,
the combination of a boiler having tubes; a
6 combustion chamber; a cooling screen in the
bottom of the chamber marginal of the zone
of combustion composed of a row of tubes,
a header into which one end of the tubes of
the screen are connected, means for anchor-
10 ing said header, a header into which the
other end of the tubes of the screen are con-
nected, a second substantially upright screen
within the chamber marginal of the zone of

combustion and composed of a row of tubes,
the lower ends of which are connected with 15
said last header, an anchored header ex-
terior of the chamber with which the upper
ends of said tubes of the upright screen are
connected, means connecting said last header
into the circulation of the boiler and means 20
for introducing fuel to be burned in suspen-
sion.

In testimony whereof, I have hereunto
signed my name.

JOHN E. BELL.

roducing the fuel to be burned in suspen-
sion.

6. In a pulverized fuel burning furnace,
the combination of a boiler having tubes; a
5 combustion chamber; a cooling screen in the
bottom of the chamber marginal of the zone
of combustion composed of a row of tubes,
a header into which one end of the tubes of
the screen are connected, means for anchor-
10 ing said header, a header into which the
other end of the tubes of the screen are con-
nected, a second substantially upright screen
within the chamber marginal of the zone of

combustion and composed of a row of tubes,
the lower ends of which are connected with 15
said last header, an anchored header ex-
terior of the chamber with which the upper
ends of said tubes of the upright screen are
connected, means connecting said last header
into the circulation of the boiler and means 20
for introducing fuel to be burned in suspen-
sion.

In testimony whereof, I have hereunto
signed my name.

JOHN E. BELL.

CERTIFICATE OF CORRECTION.

Patent No. 1,616,675,

granted February 8, 1927.

to JOHN E. BELL.

It is hereby certified that error appears in the printed specification of the
above mentioned patent requiring correction as follows: Page 2, lines 17 and 35,
claims 1 and 2 respectively, for the word "and" read "a", and line 54, claim 3,
for the word "stream" read "screen"; and that the said Letters Patent should be
read with these corrections therein that the same may conform to the record of
the case in the Patent Office.

Signed and sealed this 1st day of March, A. D. 1927.

M. J. Moore,
Acting Commissioner of Patents.
